UNITED STATES PATENT OFFICE

154,308

DESIGN FOR A FISHING REEL

Othmar W. Pies, Cincinnati, Ohio, assignor to
Aqua-Sportsman, Inc., Norwood, Ohio, a corporation of Ohio

Application October 29, 1946, Serial No. 134,374

Term of patent 14 years

(Cl. D31—4)

To all whom it may concern:

Be it known that I, Othmar W. Pies, a citizen of the United States, residing at Cincinnati, in the county of Hamilton and State of Ohio, have invented a new, original, and ornamental Design for a Fishing Reel, of which the following is a specification, reference being had therein to the accompanying drawing:

Figure 1 is an end elevation of a fishing reel, showing my new design.

Figure 2 is a rear view of the reel shown in Figure 1.

Figure 3 is a front view of the reel shown in Figure 1.

Figure 4 is a plan view of the reel shown in Figure 1.

Figure 5 is a perspective view of the reel shown in Figure 1.

I claim:

The ornamental design for a fishing reel, as shown.

OTHMAR W. PIES.
